UNITED STATES PATENT OFFICE.

JOHN E. MUHLEFELD, OF SCARSDALE, NEW YORK.

STEAM LOCOMOTIVE.

Application filed November 26, 1926. Serial No. 150,886.

This invention relates to steam locomotives, and has for its primary object to provide an improved arrangement of the cylinders for compounding or expansively utilizing the steam of high powered freight and passenger locomotives.

It is also one of the principal objects of my invention to provide a new mounting and arrangement of high and low pressure locomotive cylinders whereby the excessive amount of non-adhesive or truck weight in locomotive engines as heretofore designed and the large number of parts heretofore carried between the front and main frames of the locomotive will be avoided.

In accomplishing the above purpose, I provide a mounting and arrangement of structurally independent high and low pressure cylinders on opposite sides of the locomotive which satisfactorily takes care of all clearance requirements and in which an advantageous distribution of the weight is obtained whereby the adhesive pressure upon the rails and therefore, the tractive power of the locomotive will be enhanced.

In a practical embodiment of the invention, I provide on each side of the locomotive a forward low pressure cylinder and a rear high pressure cylinder arranged above the drivers and with its bore axis disposed at an inclination of approximately 15° , the said cylinders, together with their connecting rods being located outside of the locomotive frames.

With the above and other objects in view, the invention consists in the improved steam locomotive, and in the form, construction and relative arrangement of its several parts as will be hereinafter more fully described, illustrated in the accompanying drawings, and subsequently incorporated in the subjoined claims.

In the drawings, wherein I have disclosed one simple and practical embodiment of the invention, and in which similar reference characters designate corresponding parts throughout the several views,—

Figure 1 is a side elevation of a steam locomotive provided with my new arrangement of high and low pressure cylinders, and

Fig. 2 is a front end elevation thereof.

Heretofore, certain types of freight and passenger locomotives have been developed wherein two or three single expansion cylinders have been employed. In such designs, it has been found that there is an excessive

amount of non-adhesive or truck weight in the engine, and particularly in the case of the three cylinder type of locomotive, a large number of machine parts between the front and main frames thereof. Also, in such prior locomotive designs, the steam is not fully and economically compounded or expansively utilized.

In order to overcome the above noted disadvantageous features of prior locomotive designs and to provide for greater tractive power in a single unit than is permissible with four pairs of driving wheels, instead of arranging a single high pressure cylinder on one side of the locomotive and a single low pressure cylinder on the other side, I provide upon opposite sides of the locomotive at its forward end two low pressure cylinders 5, one on each side of the boiler smoke box indicated at 6. These cylinders may be mounted in any practical manner outside of the locomotive frames 7. Also, on each side of the locomotive rearwardly of the low pressure cylinders 5 there is arranged a high pressure cylinder 8. These low and high pressure cylinders 5 and 8 respectively, are structurally independent of each other, steam being supplied to the high pressure cylinders through pipes 9 from the superheater header 85 10 and the exhaust steam from the high pressure cylinder being supplied through pipes 11 to the low pressure cylinders 5.

It will be observed that the high pressure cylinders 8 are arranged above the driving wheels 12 of the locomotive and outside of the locomotive frames with the cylinder bore axis disposed at an inclination of approximately 15° . By so locating these high pressure cylinders with relation to the low pressure cylinders 5, a proper distribution of the weight is obtained, resulting in greater adhesive pressure on the rails and therefore, an increase in tractive power. Such arrangement also takes care of all necessary clearance requirements and permits of easy accessibility to the various parts which was not heretofore possible in those designs wherein many of the parts were arranged between the locomotive frames.

The piston rods 13 of the high pressure cylinders are provided with crossheads 14 reciprocating in suitable guides 15, connecting rods 16 being connected with crossheads 14 and with one pair of the locomotive driving wheels 12. Similar driving connections 17 are also provided between a second pair of

driving wheels and the crossheads 19 of the piston rods 18 of the pistons operating in the low pressure cylinders 5. All of these driving connections, as well as the high and low pressure cylinders are, of course, located outside of the frames 7 of the locomotive.

The compound locomotive above described utilizing two structurally independent high and low pressure cylinders on each side of the locomotive is designed for use in connection with a boiler steam pressure of 350 pounds or greater, and when operating in compound gear, will have a tractive power of approximately 85,000 pounds, the steam being exhausted from 19 x 32 inch high pressure cylinders and re-expanded in 33 x 32 inch low pressure cylinders. It will thus be apparent that not only do I provide a mounting and arrangement of the two pairs of high and low pressure cylinders which permit of easy accessibility with better weight distribution than heretofore, but I also thereby obtain a material increase in tractive power.

While I have above described and illustrated in the drawing a preferable mounting and arrangement of the cylinders upon each side of the locomotive, it will be understood that certain variations might be resorted to in the particular location and arrangement of the independent high and low pressure cylinders as expediency might require, and that I do not, of course, desire to be restricted to the precise arrangement shown. Accordingly, it is to be understood that in utilizing my present improvements, I reserve the right to adopt all such legitimate modifications in the form, construction and arrangement of the several parts as may be fairly considered as within the spirit and scope of the appended claims.

I claim:

1. In a steam locomotive, structurally independent high and low pressure cylinders mounted upon each side thereof in longitudinally spaced relation, the rear cylinders being obliquely inclined with respect to the front cylinders, and direct driving connections between the respective cylinder pistons and separate drive wheels of the locomotive.
2. In a compound steam locomotive, structurally independent high and low pressure

cylinders mounted at each side thereof upon rigid frames with the axis of one cylinder obliquely inclined relative to the axis of the other cylinder, and direct driving connections between the cylinder pistons and spaced pairs of locomotive driving wheels, said cylinders and the driving connections being located outside of the locomotive frames.

3. In a compound steam locomotive, structurally independent high and low pressure cylinders mounted upon each side of the locomotive outside of the locomotive frames, and said high pressure cylinders being spaced rearwardly from the low pressure cylinders and arranged above the locomotive driving wheels.

4. In a compound steam locomotive, structurally independent high and low pressure cylinders mounted upon each side of the locomotive outside of the locomotive frames, said high pressure cylinders being spaced rearwardly from the low pressure cylinders and arranged above the locomotive driving wheels, said high pressure cylinders being positioned at a longitudinal inclination of approximately 15° with respect to the locomotive frames, and driving connections between the pistons of the high and low pressure cylinders and spaced pairs of locomotive driving wheels.

5. In a compound steam locomotive, structurally independent high and low pressure cylinders mounted upon each side of the locomotive outside of the engine frames, said high pressure cylinders being spaced rearwardly from the low pressure cylinders and positioned above the locomotive driving wheels, connections between the steam superheater of the locomotive and the high pressure cylinders, connections between the exhaust of the high pressure cylinders and the intake of the low pressure cylinders, said high pressure cylinders having their bores obliquely inclined with respect to the engine frames, and connections between the pistons for the high and low pressure cylinders and spaced pairs of driving wheels also located outside of the engine frames.

In testimony that I claim the foregoing as my invention, I have signed my name hereto:

JOHN E. MUHLFIELD.
